waukee, Wis.

Continuation of application Serial No. 507,969,
October 28, 1943. This application May 19,
1950, Serial No. 162,901.

15 Claims. (Cl. 60—39.15)

1

This invention, originally disclosed in copending application Serial No. 507,969, filed October 28, 1943, now abandoned, of which the present application is a continuation, relates to the control and regulation of continuous combustion gas turbine systems embodying separate compressor driving and excess power developing turbines receiving motive fluid from one or more combustion chambers in which the pressure of the motive fluid is subject to change in response to variations in the quantity of motive fluid entering the power turbine and has for its primary object the maintenance of a high degree of overall system efficiency as the load output of the power turbine varies.

More particularly, the invention resides in varying the flow capacity and the power output of the compressor turbine as the quantity of fluid entering the power turbine changes in order to compress and deliver to the combustion chamber a quantity of air commensurate with the power requirements of both turbines. In other words, the flow capacity and the power output of the compressor turbine are varied as the load on the power turbine changes in order to develop and apportion to said turbines motive fluid commensurate in quantity and energy content with their respective load requirements.

Accordingly, the invention consists of the various procedures, correlations of features and arrangements of parts as is more fully set forth in the appended claims and in the detailed description, in which:

Fig. 1 schematically illustrates a continuous combustion turbine system embodying the invention; and

Fig. 2 illustrates a modifying connection between the power turbine governor and the pressure and temperature responsive devices.

Referring to the drawing, it is seen that a continuous combustion gas turbine system embodying the invention may include a combustion gas generating means or combustion chamber 1 provided with a fluid fuel burner 2 to which fuel is supplied from a suitable source (not shown) through a pipe 3 in which is disposed a regulating valve 4, a compressor 6 delivering air to the burner end of combustion chamber 1 through a conduit 7, a multistage turbine 8 drivingly connected with the compressor 6 and having a first or high and one or more intermediate pressure stage inlet portions 9, 11 and 12 connected with the opposite or discharge end of combustion chamber 1 by means of conduits 13, 16 and 14, respectively, valves 17 and 18 controlling the flow

5 of gas through conduits 14 and 16, respectively, and an excess power developing turbine 19 drivingly connected with an electric generator 21 and having an inlet portion 22 connected with the discharge end of combustion chamber 1 by means of a conduit 23 in which is disposed a suitable throttle valve 24.

10 A governor 26 responsive to changes in the speed of compressor turbine 8 and a governor 27 responsive to changes in the speed of power turbine 19 have reciprocable elements 28 and 29, respectively, interconnected for jointly and severally actuating the regulating valve 4 by means of a floating lever 31 having one end connected with element 28, a lever 32 which is fulcrumed intermediate its ends at 33 and has one connected with element 29, a link 34 interconnecting the adjacent ends of levers 31 and 32, a link 36 connecting an intermediate portion of lever 31 with 15 one end of a floating lever 37, a link 38 connecting an intermediate portion of lever 37 with one arm of a bell crank lever 39 and a link 41 connecting the other arm of bell crank lever 39 with the valve 4. The opposite end of floating lever 37 is connected by means of a link 42 with an intermediate portion of a floating lever 43 which has its opposite ends connected with temperature and 20 pressure regulating or limiting devices 44 and 46, respectively, for movement jointly and severally as the temperature and/or pressure of the gas within the combustion chamber varies or exceeds predetermined limits. The throttle valve 24 in conduit 23 is operatively connected with the element 29 of governor 27 for movement therewith by means of a bell crank lever 47 and a link 48.

25 The hereinbefore described interconnection of governors 26 and 27 is such that when the system is in operation, an increase in the speed of compressor turbine 8 (in any system embodying the invention, the speed of the compressor is always the same or proportional to that of the turbine driving same) results in an upward movement of element 28, a clockwise movement of floating lever 31 about its point of pivotal connection with link 34, an upward movement of link 36, a clockwise movement of floating lever 37 about its point of pivotal connection with link 42, an upward movement of link 38, a clockwise movement of bell crank lever 39, a movement of link 41 toward the left, and a closing movement of valve 4. Obviously, if the speed of the compressor turbine decreases, the element 28 of governor 26 moves downward and effects an opening movement of the valve 4. However, if the speed of the power turbine 19 increases, the element 29 of governor 27 moves

downward effecting a clockwise movement of bell crank lever 47 and a consequent closing movement of throttle valve 24 and in addition effects a clockwise movement of lever 32 and thereby an upward movement of link 34, a counterclockwise movement of floating lever 31 about its point pivotal connection with element 29 of governor 26, and an upward movement of link 36 which movement, as previously described in connection with operation of governor 26, effects a closing movement of the valve 4. Obviously, a decrease in the speed of power turbine 19 will move element 29 of governor 27 in the opposite direction and effect an opening movement of both valves, that is, the valves designated 4 and 24.

The valves 17 and 18 in conduits 14 and 16 are arranged to be sequentially opened and closed by a servomotor 49 having a piston 51 provided with oppositely extending stem or rod portions 52 and 53 of which rod portion 53 is connected with an intermediate portion of a lever element 54 having its opposite ends connected with the valves 17 and 18 by means of links 56 and 57, respectively, and of which rod portion 52 is connected with one end of a lever 58 which is fulcrumed intermediate its end at 59 and has its other end connected with an intermediate portion of a floating lever 61 by means of a link 62. One end of lever 61 is connected by a link 63 to a portion of lever 32 intermediate its fulcrum 33 and its point of connection with governor element 29 and the other end of lever 61 is connected with the stem of a balanced pilot valve 64 which controls the connection between the fluid supply pipe 66 and the pipes 67 and 68 and between the pipes 67 and 68 and the drain or return pipes 69 and 71, respectively; the construction being such that when the valve 64 is in its neutral or shown position no fluid flows into or out of servomotor 49, that when the valve 64 is moved downward from the position shown, fluid under pressure is admitted to the upper side of piston 51 through pipe 67 and the fluid beneath the piston is free to flow therefrom through pipes 68 and 71, that when the valve is moved upward from the position shown, fluid under pressure is admitted to the underside of piston 51 through pipe 68 and the fluid at the upper side of the piston is free to flow therefrom through pipes 67 and 69, and that the resulting movement of piston 51 effects a return of pilot valve 64 to its neutral position.

Upward movement of the left hand end of lever element 54 is resisted and limited by a compression spring 72 interposed between said end of the element and a fixed support 73 and upward movement of the right hand end of element 54 aided by a tension spring 75 and is limited by an adjustable stop 74. Consequently, as the servomotor piston 51 moves upward from its shown position, lever element 54 moves in a counterclockwise direction about its point of pivotal connection with link 56 and until the right hand end thereof engages stop 74 after which a further upward movement of piston 51 results in lever element 54 moving in a clockwise direction about its point of pivotal connection with link 57 and until the spring 72 is fully compressed; further upward movement of the servomotor piston and damage to the parts normally actuated by the rod portion 53 thereof being permitted and prevented, respectively, by the resiliently interconnected parts 76 of rod portion 53.

It should now be obvious that an upward movement of servomotor piston 51 from its shown position first moves valve 18 from its fully closed

to its fully open position, that a further upward movement of piston 51 moves valve 17 from its fully closed to its fully open position, and that the opening of valves 18 and/or 17 as just described reduces the number and/or effectiveness of the active or power producing stages in the turbine 8 which materially decreases the resistance to the flow of gas therethrough and thereby greatly increases its flow capacity.

The movement of pilot valve 64 away from its neutral position is effected by the governor 27 of power turbine 19; the arrangement being such that when the speed of the power turbine increases, it being assumed that the various parts are shown as positioned to obtain a maximum power output from both turbines, the element 29 of governor 27 will move downward and simultaneously effect (a) a closing movement of throttle valve 24, (b) a closing movement of fuel valve 4, and (c) an upward movement of pilot valve 64 which in turn operates servomotor 49 to move valve 18 toward its fully open position. A partial closing of throttle valve 24 tends to increase the pressure of the motive fluid within combustion chamber 1 and as a result the speed of the compressor may increase sufficiently to deliver more air to the combustion chamber and to render governor 26 operable to effect a further closing movement of fuel valve 4. However, although the delivery of more air to the combustion chamber does tend to further increase the pressure of the motive fluid, the closing movement of fuel valve 4 reduces the heat input and thereby the temperature and to some extent the pressure of the motive fluid while a partial opening of valve 18 also operates to reduce the pressure of the motive fluid by decreasing the resistance to the flow of motive fluid through the turbine 8 which in turn increases its flow capacity with a corresponding decrease in the power developed thereby.

Obviously, with the parts positioned as previously assumed, the extent to which the throttle and fuel regulating valves 24 and 4, respectively, are closed and the extent to which the valves 18 and/or 17 are opened depends entirely upon how much load is removed from the power turbine 19. If, for example, the load on the power turbine drops to zero, the throttle valve 24 will be nearly or fully closed, the fuel regulating valve 4 will remain open sufficiently to meet the heat input power requirements of the compressor turbine, and the valves 18 and 17 will be fully open. If when the valves are positioned as just described, the load on the power turbine increases, the speed will commence to decrease and the element 29 of governor 27 will move upward effecting a counterclockwise movement of lever 32 and a consequent opening movement of fuel valve 4 and a downward movement of pilot valve 64; the latter admitting fluid under pressure to the top side of piston 51 which moves downward and effects a counterclockwise movement of lever element 54 about its point of pivotal connection with link 57 and thereby a closing movement of valve 17. The primary function of tension spring 75 being to hold the right hand end of lever element 54 against stop 74 until the valve 17 is fully closed whereupon a further downward movement of piston 51 causes lever element 54 to pivot clockwise about its point of connection with link 56 and move valve 18 toward its fully closed position against the action of spring 75.

As previously indicated, a closing movement of throttle valve 24 increases the resistance to the

flow of motive fluid through the conduit 23 and thereby tends to increase the pressure of the motive fluid within the combustion chamber while the opening of valves 17 and 18 reduces the resistance to the flow of motive fluid through the turbine 8 and thereby tends to decrease the pressure of the motive fluid; the opening and closing movement of the valves 17, 18 and 24 being preferably so correlated in the illustrated system that the pressure of the motive fluid within the combustion chamber increases and decreases as the load on the power turbine increases and decreases, respectively. In this connection, the power developed by compressor turbine 8 is proportional to the drop in pressure and temperature of the gases passing therethrough and by properly selecting the number and location of the inlets to the intermediate pressure stages of the compressor turbine and by properly correlating the admission of motive fluid to said inlets with the admission of motive fluid to the power turbine, the power developed by the compressor turbine and thereby the quantity of air delivered to the combustion chamber can be readily varied in accordance with the power requirements of the system for all conditions of load while maintaining the air near the maximum permissible operating temperature in order to obtain high efficiency. The number and the location of the inlets to the intermediate stages of the compressor turbine and the particular manner in which the admission of motive fluid to said inlets is correlated with the admission of motive fluid to the power turbine is of course dependent upon the operating characteristics of the turbines and compressor which can be readily determined by any one skilled in the art and having once determined said characteristics and the nature of load to be carried by the system upon whether the best efficiency for a changing load is obtained by varying the quantity and the temperature and/or pressure of the motive fluid or by merely varying the quantity of motive fluid while maintaining its temperature and pressure at the optimum values.

In the disclosed embodiment of the invention, the turbine and compressor characteristics and the nature of load may be assumed to be such that maximum thermal efficiency is obtained by maintaining the temperature of the motive fluid substantially constant at a predetermined value throughout the entire load range. Consequently, the position of the fuel regulating valve 4 and thereby the heat input to the system is controlled jointly and severally by governors 26 and 27 in order to maintain the temperature of the motive fluid substantially constant as the load on the power turbine varies and the positions of valves 17, 18 and 24 are controlled by governor 27 in order to vary and apportion the quantity of motive fluid flowing through the turbines in accordance with their respective load requirements while maintaining the pressure of the motive fluid within the combustion chamber at an optimum value; the function of the temperature and pressure responsive devices 44 and 46 being in this case to terminate operation of the system whenever the temperature and/or pressure of the motive fluid exceeds predetermined maximum limits. However, if the operating characteristics of the turbines and compressor and nature of the load to be carried by the system are such as to necessitate varying the quantity and the temperature and/or pressure of the motive fluid in order to obtain the best overall efficiency, this can be readily done with the illustrated appara-

tus simply by modifying one or both of the temperature and pressure responsive devices 44 and 46, for example, by extending lever 58 and interposing a compression spring 77 between the extended end of lever 58 and the adjacent end of floating lever 37 as indicated in Fig. 2, so that the temperature and/or pressure of the motive fluid is varied by changing the heat input and/or by changing the extent to which the valves 17, 18 and 24 are opened and closed in response to a predetermined degree of load change.

The invention is applicable to all types of combustion turbine systems embodying separate compressor driving and excess power developing turbines and although the invention has been shown and disclosed in connection with a system embodying only one combustion chamber and only one compressor driving and one excess power developing turbine, it should be understood that it is not desired to limit the invention to the exact details of construction and modes of operation herein shown and described, as various modifications within the scope of the claims may occur to persons skilled in the art.

25 It is claimed and desired to secure by Letters Patent:

1. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving shafts; means severally connecting an inlet to said compressor turbine and an inlet to said power turbine with said generating means; means responsive to change in load on said power turbine; means responsive directly and solely to said load responsive means for varying the flow of gas to said power turbine; and means responsive to said load responsive means for varying the flow through said fuel inlet.

2. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving shafts; means severally connecting an inlet to said compressor turbine and an inlet to said power turbine with said generating means; means responsive to change in load on said power turbine; valve means for controlling the flow of gas to said power turbine in response to said load change responsive means to increase and decrease said flow in the same sense as change in load; valve means for controlling the flow of fuel through said fuel inlet in response to said load change responsive means to increase and decrease said fuel flow in the same sense as change in load; second load responsive means responsive to changes in load on said compressor turbine; and means responsive to said second load responsive means for controlling said fuel valve means to increase and decrease the fuel flow in the same sense as change in load on said compressor turbine.

3. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving

shafts; means severally connecting an inlet to said compressor turbine and an inlet to said power turbine with said generating means; means responsive to change in load on said power turbine; means responsive to said load responsive means for varying the flow of gas to said power turbine; second load responsive means responsive to the load on said compressor turbine; and means responsive to said second load responsive means for varying the flow through said fuel inlet.

4. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving shafts; means severally connecting an inlet to said compressor turbine and an inlet to said power turbine with said generating means; means responsive to change in load on said power turbine; means responsive directly and solely to said load responsive means for varying the flow of gas to said power turbine; means responsive to said load responsive means for varying the flow through said fuel inlet; second load responsive means responsive to changes in load on said compressor turbine; and means responsive to said second load responsive means for varying the flow through said fuel inlet.

5. A gas turbine system, comprising: a combustion gas generating means having a fuel inlet; a compressor delivering air to said generating means; a multistage turbine drivingly connected with said compressor and having separate inlets for the first and one or more intermediate stages thereof; an excess power developing turbine; said compressor turbine and said power turbine having separately rotatable driving shafts respectively; means severally connecting said separate inlets for the first and one or more intermediate stages of said compressor turbine and the inlet to said power turbine directly with said generating means, and means responsive to change in load on said power turbine for controlling the direct flow of gas to an intermediate stage of said compressor turbine.

6. A gas turbine system, comprising: a combustion gas generating means having a fuel inlet; a compressor delivering air to said generating means; a multistage turbine drivingly connected with said compressor and having separate inlets for the first and one or more intermediate stages thereof; an excess power developing turbine; said compressor turbine and said power turbine having separately rotatable driving shafts respectively; means severally connecting said separate inlets for the first and one or more intermediate stages of said compressor turbine and the inlet to said power turbine with said generating means, and means responsive to change in load on said power turbine for controlling the direct flow of gas to an intermediate stage of said compressor turbine; second load responsive means responsive to change in load on said compressor turbine; and means responsive to said second load responsive means for varying the flow through said fuel inlet.

7. A gas turbine system, comprising: a combustion gas generating means; a compressor delivering air to said generating means; a multistage turbine drivingly connected with said compressor and having separate inlets for the first and one or more intermediate stages thereof; an excess power developing turbine; said com-

pressor turbine and said power turbine having separately rotatable driving shafts respectively; means severally connecting said separate inlets for the first and one or more intermediate stages of said compressor turbine and the inlet to said power turbine directly with said generating means; means responsive to change in load on said power turbine; valve means responsive to said load responsive means interposed between said inlet to said power turbine and said generating means for controlling the flow of gas to said power turbine; and valve means responsive to said load responsive means interposed between an intermediate stage of said compressor turbine and said generating means for controlling the direct flow of gas from said generating means to said intermediate stage.

8. A gas turbine system, comprising: a combustion gas generating means; a compressor delivering air to said generating means; a multistage turbine drivingly connected with said compressor and having separate inlets for the first and one or more intermediate stages thereof; an excess power developing turbine; said compressor turbine and said power turbine having separately rotatable driving shafts respectively; means severally connecting said separate inlets for the first and one or more intermediate stages of said compressor turbine and the inlet to said power turbine directly with said generating means; means responsive to change in load on said power turbine; valve means responsive to said load responsive means interposed between said inlet to said power turbine and said generating means for controlling the flow of gas to said power turbine to increase and decrease said flow in the same sense as change in load; and valve means responsive to said load responsive means interposed between an intermediate stage of said compressor turbine and said generating means for controlling the direct flow of gas from said generating means to said intermediate stage to increase and decrease said flow in the opposite sense of change in load.

9. A gas turbine system, comprising: a combustion gas generating means having a fuel inlet; a compressor delivering air to said generating means; a multistage turbine drivingly connected with said compressor and having separate inlets for the first and one or more intermediate stages thereof; an excess power developing turbine; said compressor turbine and said power turbine having separately rotatable driving shafts respectively; means severally connecting said separate inlets for the first and one or more intermediate stages of said compressor turbine and the inlet to said power turbine directly with said generating means; means responsive to change in load on said power turbine; valve means responsive to said load responsive means interposed between said inlet to said power turbine and said generating means for controlling the flow of gas to said power turbine; valve means responsive to said load responsive means interposed between an intermediate stage of said compressor turbine and said generating means for controlling the direct flow of gas from said generating means to said intermediate stage; and valve means responsive to said load responsive means for controlling the flow through said fuel inlet.

10. A gas turbine system, comprising: a combustion gas generating means having a fuel inlet; a compressor delivering air to said generating means; a multistage turbine drivingly connected with said compressor and having separate inlets for the first and one or more intermediate stages thereof; an excess power developing turbine; said com-

nected with said compressor and having separate inlets for the first and one or more intermediate stages thereof; an excess power developing turbine; said compressor turbine and said power turbine having separately rotatable driving shafts respectively; means severally connecting said separate inlets for the first and one or more intermediate stages of said compressor turbine and the inlet to said power turbine directly with said generating means; means responsive to change in load on said power turbine; means responsive directly and solely to said load responsive means for varying the flow of gas to said power turbine; means responsive to said load responsive means for varying the direct flow of gas to an intermediate stage of said compressor turbine; and means responsive to said load responsive means for varying the flow through said fuel inlet.

11. A gas turbine system, comprising: a combustion gas generating means having a fuel inlet; a compressor delivering air to said generating means; a multistage turbine drivingly connected with said compressor and having separate inlets for the first and one or more intermediate stages thereof; an excess power developing turbine; said compressor turbine and said power turbine having separately rotatable driving shafts respectively; means severally connecting said separate inlets for the first and one or more intermediate stages of said compressor turbine and the inlet to said power turbine directly with said generating means; means responsive to change in load on said power turbine; means responsive directly and solely to said load responsive means for varying the flow of gas to said power turbine; means responsive to said load responsive means for varying the direct flow of gas to an intermediate stage of said compressor turbine; means responsive to said load responsive means for varying the flow through said fuel inlet; second load responsive means responsive to changes in load on said compressor turbine; and means responsive to said second load responsive means for varying the flow through said fuel inlet.

12. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving shafts; means severally connecting an inlet to said compressor turbine and an inlet to said power turbine with said generating means; means responsive to change in load on said power turbine; valve means associated with said power turbine inlet responsive directly and solely to said load responsive means for varying the flow of gas to said power turbine; and means responsive to said load responsive means for varying the flow through said fuel inlet.

13. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving shafts; means severally connecting an inlet to said compressor turbine and an inlet to said power turbine with said generating means; means responsive to change in load on said power turbine; valve

means associated with said power turbine inlet and responsive to said load responsive means for varying the flow of gas to said power turbine in the same sense as the change in load on said power turbine; second load responsive means responsive to the load on said compressor turbine; and means responsive to said second load responsive means for varying the flow through said fuel inlet.

14. A gas turbine system, comprising: a combustion gas generating means having a fuel inlet; a compressor delivering air to said generating means; a turbine drivingly connected with said compressor; an excess power developing turbine; said compressor turbine and said power turbine having separately rotatable driving shafts; means directly and severally connecting an inlet to said compressor turbine and an inlet to said power turbine with said generating means; means responsive to change in load on said power turbine; valve means associated with said power turbine inlet and responsive solely to said load responsive means for varying the flow of gas to said power turbine in the same sense as the change in load on said power turbine; means responsive to said load responsive means for varying the flow through said fuel inlet; second load responsive means responsive to changes in load on said compressor turbine; and means responsive to said second load responsive means for varying the flow through said fuel inlet.

15. A gas turbine system, comprising: a combustion gas generating means having a fuel inlet; a compressor delivering air to said generating means; a multistage turbine drivingly connected with said compressor and having separate inlets for the first and one or more intermediate stages thereof; an excess power developing turbine; said compressor turbine and said power turbine having separately rotatable driving shafts respectively; means directly and severally connecting said separate inlets for the first and one or more intermediate stages of said compressor turbine and the inlet to said power turbine with said generating means; means responsive to change in load on said power turbine; valve means associated with said power turbine inlet and responsive directly and solely to said load responsive means for varying the flow of gas to said power turbine; means responsive to at least one of said intermediate stage inlets and responsive to said load responsive means for varying the direct flow of gas to an intermediate stage of said compressor turbine; means responsive to said load responsive means for varying the flow through said fuel inlet; second load responsive means responsive to changes in load on said compressor turbine; and means responsive to said second load responsive means for varying the flow through said fuel inlet.
